UNITED STATES PATENT OFFICE.

CHARLES O. CARLSON, OF PORT RICHMOND, NEW YORK.

GAS-ENGINE.

No. 882,812.

Specification of Letters Patent. Patented March 24, 1908.

Application filed April 12, 1907. Serial No. 367,863.

To all whom it may concern:

Be it known that I, CHARLES O. CARLSON, a resident of Port Richmond, Staten Island, in the county of Richmond and State of New York, have invented a new and useful Improvement in Gas-Engines; and I do hereby declare the following to be a full, clear, and exact description thereof.

My invention relates to gas engines, its object being to provide a novel and simple form of mechanism by means of which the air may be forced into the cylinder after the explosion in order to scavenge the same and prepare the cylinder for the next charge.

To these ends my invention comprises the novel features hereinafter set forth and claimed.

In the accompanying drawings Figure 1 is a vertical sectional elevation of my improved gas engine; Fig. 2 is a like view showing the piston in compression; Fig. 3 is a like view showing the piston and valve mechanism in position where the piston is about to ascend to compress the charge; Fig. 4 is an enlarged detail view of a portion of the cylinder and valve mechanism; Fig. 5 is detail view of the cam for operating the exhaust valve; Fig. 6 is a section on the line 6—6, Fig. 4.

In the drawings the numeral 2 designates a suitable cylinder provided with a suitable water jacket 3, said cylinder being illustrated in upright form and supported by the section 4 forming the guide for the cross head 5. This section 4 is bolted or secured to the closed crank case 6. Within the cylinder 2 is the cup-piston 7 to which the piston rod 8 is secured, said piston rod passing down through a suitable stuffing box 9 in the diaphragm 10 which separates the lower chamber 11 of the cylinder from the cross head casing 4. The cross head 5 is secured to the piston 8 and a pitman 12 connects said cross head to the crank 13 on the engine shaft 14. At the upper end of the cylinder 2 is the valve 15 which controls the supply of explosive mixture entering the port 16.

The cylinder 2 is provided with the exhaust port 17 controlled by the valve 18. This valve 18 has the stem 19 which passes down through the guides 20 and to the lower end of said rod is secured the yoke 21 which fits over the shaft 22. On said yoke is the friction roller or pin 23 in the path of the cam 24 secured to the shaft 22. This shaft 22 has on it a bevel gear 25 meshing with the

bevel gear 26 on the shaft 27. The shaft 27 has at its inner end the bevel gear 28 which meshes with the bevel gear 29 upon the shaft 30. The shaft 30 is parallel to the engine shaft 14 and on said shaft is the gear wheel 31 which meshes with the pinion 32 upon the engine shaft 14. In this manner power is transmitted from the engine shaft to the shaft 22 to operate the cam which raises the exhaust valve 18 as fully hereinafter set forth.

Within the valve casing 33 on the cylinder 2 is the valve 34 controlling the port 35 leading to the upper chamber of the cylinder at a point just above the lowest position of the piston, and the port 36 which communicates with the passage 37 leading to the chamber 11 of the cylinder below the piston. A main air inlet 38 is connected up to the valve casing 33 and communicates with the annular passage 39 which is adapted to be brought into communication with the port 36 leading into the passage 37, as fully hereinafter set forth. This air-inlet 38 communicates with the atmosphere. Connected to the valve 34 is a stem or rod 40, the lower end of said rod having the yoke 41 secured thereto engaging the shaft 22. A friction roller or pin 42 is carried by the yoke 41 and said pin fits within the cam-way 43 of the cam disk 44 secured to the shaft 22.

When my improved gas engine is in operation, the charge of explosive mixture is first drawn through the valve 15 which is lowered by the descent of the piston 7, the exhaust valve being closed and the valve 34 being in position to close the ports 35 and 36. The explosive mixture being drawn in by the descent of the piston, the piston then ascends to compress the charge which is thereupon ignited in the ordinary way to create the explosion. The piston in the meantime, upon its upward stroke to compress the explosive mixture has drawn in the air through the inlet 38, the valve 34 having been moved by the cam 44 so as to bring the annular passage into register with the port 36, whereby the air passes into the passage 37, being drawn into the chamber 11 of the cylinder by the suction of the piston as said piston ascends to compress the charge. Upon the descent of the piston after the explosion, the valve 34 is moved to the position indicated in Fig. 2 so as to close the ports 35 and 36. As said piston descends, the air admitted to the chamber 11 below the piston is gradually compressed and just before said piston opens the

port 35 the action of the cam operates to lift the exhaust valve 18, permitting the foul gases to escape through said valve and by the time said piston 7 has passed the port 35 5 the cam 44 will have moved the valve 34 into the position indicated in Fig. 1, whereupon the air compressed within the chamber 11 is forced up through the passage 37, the port 36, through the valve 34 and passage 35 into the 10 cylinder 2 just above the piston 7 when in its lowest position. This air being admitted to the cylinder 2 at this point under compression acts to drive out the foul gases, the valve 18 remaining open a sufficient length of time 15 to permit of this. In this manner the air entering the cylinder above the piston acts to scavenge the cylinder and clean it thoroughly so as to prepare it for the admission of another charge of the explosive mixture. 20 The operation of the cams 24 and 44 are timed so that just as the piston is about to descend to draw in the new charge of the explosive the valve 18 is closed and the valve 34 is brought to the position indicated in Fig. 25 2. In this manner, as the piston ascends, the valves 18 and 34 are so operated as to open and close the exhaust and draw the fresh air into the cylinder below the piston and force said air into the space above the 30 piston so as to thoroughly scavenge the cylinder. The valve mechanism may be timed with great accuracy so as to operate at the proper periods to give the results above described.

35 What I claim is:

1. In a gas engine, the combination of a cylinder, a piston therein, a piston rod, connections between said rod and the engine shaft, a gas inlet port at the upper end of said 40 cylinder, an exhaust valve, a main air port, an air port leading to the upper portion of said cylinder at a point just above the lowest position of said piston, a second air port leading to the lower end of said cylinder, a valve 45 controlling said ports and means for operating said valve, whereby air is drawn into

the lower end of said cylinder by the ascent of said piston, compressed therein, and admitted to the upper end of said cylinder when said piston in its descent passes the air 50 port leading thereto.

2. In a gas engine, the combination of a cylinder, a piston therein, a piston rod, connections between said rod and engine shaft, a gas inlet port at the upper end of said cylinder, an exhaust valve, a main air port, an air port leading to the upper portion of said cylinder at a point just above the lowest position of said piston, a second air port leading to the lower end of said cylinder, a valve controlling said ports, cam mechanism for operating said valve, connections between said cam mechanism and the engine shaft, whereby air is drawn into the lower end of said cylinder by the ascent of said piston, compressed therein and admitted to the upper end of said cylinder when said piston in its descent passes the air port leading thereto. 55

3. In a gas engine, the combination of a cylinder, a piston therein, a piston rod, connections between said rod and the engine shaft, a gas inlet port at the upper end of said cylinder, an exhaust valve, a main air port communicating directly with the atmosphere, an air port leading to the upper portion of said cylinder at a point just above the lowest position of said piston, a second air port leading to the lower end of said cylinder, a valve controlling said port and means for operating said valve whereby air is drawn 70 into the lower end of said cylinder by the ascent of said piston, compressed therein, and admitted to the upper end of said cylinder when said piston in its descent passes the air 75 port leading thereto. 80

In testimony whereof, I the said CHARLES O. CARLSON have hereunto set my hand.

CHARLES O. CARLSON.
